BUFFING WHEEL

Fritz E. Hendrickson, South Elgin, Ill., assignor
of one-half to Murray Ireland, Elgin, Ill.

Application May 24, 1951, Serial No. 228,003

6 Claims. (Cl. 51—193)

1

This invention relates to improvements in buffing wheels, and more particularly to a flexible buffing wheel construction in which an endless buffing element is removably attached to a central mounting part or hub.

Previous constructions of buffing wheels have been subject to certain disadvantages, not only in assembly and disassembly but also in construction and use. These disadvantages have occasioned excessive amounts of time in assembling and disassembling a wheel, as well as high costs of operation and inefficient, unsatisfactory results in their use. It has been a common practice in this art of providing flexible buffing elements gathered or bunched around the periphery of the central hub or mounting part and extending radially outward thereof. While this may provide a "soft" wheel at its periphery when new, it becomes increasingly "hard" as wear reduces the working diameter into the bunched fabric. As a result of this change in buffing character, the fabric elements are frequently replaced causing a considerable loss of operating time, increased assembly time, and high cost by waste of fabric.

The present invention seeks to eliminate the foregoing objectionable features by providing a buffing wheel construction having a central hub or mounting element on which there are peripherally spaced outwardly tapered fingers, an endless strip type buffing fabric arranged to be mounted on the fingers and folded in such a manner as to effect a wider buffing area, softer buffing characteristics throughout its working diameter, increased ventilation efficiency, and a reduction in fabric waste, and retainers coacting with the mounting fingers to pressure lock the mounted fabric thereon.

Therefore, it is an important object of this invention to provide a buffing wheel which is so constructed that it can be assembled and disassembled easily and quickly.

A further object is to provide a buffing wheel of such construction as to effect uniform buffing characteristics throughout the entire working diameter of the buffing element.

Another and further object is to provide a buffing wheel having an endless buffing element so folded in operative arrangement as to effect a wider buffing area and more efficient centrifugal ventilation.

Still another object is to provide a continuous strip buffing element folded, rather than cut, to desired shape and form to eliminate waste of fabric.

Still another and further object is to provide a continuous buffing element so folded in opera-

2

tive arrangement as to form spaced pockets along the length thereof.

Yet another object is to provide a buffing wheel having a center mount and a fabric buffing element effectively and detachably secured around the periphery of said mount by novel attachment means effecting a readily releasable engagement of the attached parts.

A still further object is to provide a buffing wheel comprising a center mount having extending fingers on which are mounted an endless buffing element retained thereon against release by separate and removable retainer means.

Yet another and still further object is to provide a buffing wheel comprising a center mount having tapered fingers each of which effect a pressure engagement between a buffing element and a removable retainer mounted thereon.

Other and further objects of the invention will become apparent to those skilled in the art from the following detailed description of the annexed sheets of drawings, which disclose preferred embodiments of the invention.

On the drawings:

Figure 1 is a face view of a buffing wheel constructed according to the principles of the present invention, a portion of the buffing element being broken away to better show the folding arrangement;

Figure 2 is a top view in elevation of the buffing element as seen when looking down on the periphery of the wheel shown in Figure 1 and with the margins of the buffing element extending directly away from each other;

Figure 3 is a view similar to Figure 2, illustrating the buffing element with the marginal portions thereof folded toward each other in operative arrangement;

Figure 4 is a fragmental radial cross-sectional view taken along the line 4—4 of Figure 1;

Figure 5 is a perspective view of the endless fabric buffing element showing the folded arrangement thereof in a form ready for mounting on a central hub;

Figure 6 is a front face view of a locking or retainer member;

Figure 7 is a face view of a central mounting hub on which a mounted buffing element is locked by the retainer member; and,

Figure 8 is a side view in elevation of the retainer member.

As shown on the drawings:

Referring now in detail to the several figures, the numeral 10 generally designates a buffing element which comprises one or more thicknesses of strip textile material. These strips 11, 11 are cut on a bias with respect to the weave to re-

sist ravelling and yet provide a soft, frayed buffing edge. The ends of the strips are stitched together, as shown by the seam 12 in Figure 5, to form endless bands of tubular shape. Any number of plies or bands 11 may be laid up in nested concentric relation, the number shown in the drawings merely being illustrative.

In the nested relation, plies or bands 11 are folded across the width thereof to provide pleats 13, 13 preferably of rectangular shape and uniform size. It is preferred that the pleats be uniformly spaced along the length of the bands for a purpose to be more apparent hereinafter. If desired, a buffing element of greater working width may be effected by again folding the bands across the pleats to provide additional pleats. As folded, the pleated bands are stitched or otherwise secured together along the spaced seams 14 and 15 extending medially lengthwise of the bands. Centrally located in the pleats and between the spaced seams are elongated mounting openings 16, 16. It has been found desirable to reinforce the pleats around the openings by strips 17, 17 of fabric heavier than the plies or bands, in which case the seams 14 and 15 also secure them in place. It is in this folded form that the buffing fabric is applied to a central mounting or driving hub 18.

The mounting hub has a plate or washer 19 on one side to provide proper spacing when a plurality of buffing wheels are combined to form a composite wheel. Mounting fingers 20, 20 extend radially outward of the hub and are uniformly spaced around its periphery. It is to be noted that the side edges 21 and 22 of each finger taper outwardly toward each other for a purpose which later will be more fully explained. In diametrical alignment with each finger and in the body of the hub are two openings 23 and 24.

A retainer lock 25 (Figure 6) has a vertically extending body 26 terminating at its lower end in a hook 27 and at its upper end in an enlarged, generally oval-shaped portion 28. Extending medially along the length of the enlarged end portion is an angular offset 29, facing in the same direction as the hook, and a flat bearing plate 30. Centrally of the offset is an elongated opening 31 of sufficient width and length to receive therethrough the upper end portion of a finger 20. An outwardly depressed locking button 32 is provided in the lower portion of the retainer lock body in axial alignment with the opening 31. The button and hook are spaced to engage within the openings 23 and 24, respectively, in the mounting hub. As best shown in Figure 4, when the retainer lock is applied to a finger on the hub the end of the finger extends through the opening 31 and bears against the bearing plate 30, and the locking button 32 and hook 27 extend, respectively, through the openings 23 and 24.

The buffing element 10, as shown in Figure 5, is applied to the central hub 18 in the following manner. The hook end and narrow body of a retainer lock 25 are inserted through an opening 16 of the pleated band or buffing element from the outer or reinforced side thereof. One of the fingers 20 on the mounting hub is then inserted, from the inside of the buffing element, through the opening 16 in face engagement with the retainer lock and through the opening 31 therein. Pressure is applied against the enlarged end of the retainer lock to force the lock to a position in which the hook end 27 and locking button 32 respectively enter the hub openings 24 and 23. As pressure is applied to effect interlocking of the

retainer and finger, the buffing element is forced downwardly on the tapered edges of the finger. This action stretches the fabric to lengthen the elongated opening 16. As the folded and reinforced fabric tends to resist stretching, it effects an inward pressure against the opposite tapered edges of the finger. As a result, the fabric is forced and maintained against the enlarged end of the retainer lock. Furthermore, the stretching of the fabric to lengthen the opening 16 effects a reduction of its width with a resulting pressure against opposite faces of the retainer and finger thereby maintaining them in interlocked relation.

In a similar manner, the succeeding pleated portions of the buffing element are applied and locked to a mounting finger. As many folded portions are provided as there are mounting fingers. It is desired that the pleats be uniformly spaced to provide similar lengths of unfolded strip material therebetween. The length of the folded buffing element (Figure 5) is greater than the circumference taken around the ends of the mounting fingers. As a result, the strip portions 33 are folded radially of the hub to provide loose pleats 34, 34. It is preferred that each of the marginal portions of the buffing element on either side of the medial seams be wider than the radial length of the pleats 34. This arrangement provides an initial peripheral exposure, as buffing surfaces, of the wave-like edges of the marginal portions when they are folded toward each other to effect an annular disk.

As shown in Figures 1 and 3, the buffing element in operative form is so distorted and bunched by the folding as to produce cup-shaped internal pockets, such as 35 in Figure 3, at each of the mounting fingers. The side walls of the pockets are formed by portions of the margins 11a and 11b of the buffing element and the end walls by the radially extending folds 34. It is preferred, as shown, to so fold the buffing element bands that each end wall of a pocket includes an end of a pleat 13 and an overlapping fold of a radially extending pleat 34. Also, that the outward end of the radial fold or pleat terminate below the peripheral working edges of the margins of the buffing element when folded toward each other (see Figure 4). By these provisions, the folds progressively form working surfaces as the diameter of the buffing element decreases. As all of the pleats in the buffing element extend generally radially outward of the mounting hub and are uniformly folded along their length, a buffing element is effected in which "soft" buffing characteristics are maintained without appreciable change during the entire working life of the wheel. Should it be desired, the reinforcing strips 17 can be provided of sufficient length to extend along the end walls of the buffing element pockets and either terminate at or below the peripheral working edge of the element. This provision effects a change in the buffing characteristics dependent, of course, on the thickness and hardness of the fabric. Also, the pockets 65 are reinforced along the entire length of the ends thereof providing strength in the fabric during the working life of the buffing element. In addition to the foregoing, the direction, size and uniformity of passageways resulting from the folding 70 promote more efficient radial ventilation of the wheel thereby extending its working life.

It is to be understood that the form of my invention herewith shown and described, is to be taken as a preferred embodiment of the same, and that various changes and modifications in form

and structure may be resorted to, without departing from the spirit of my invention, or the scope of the appended claims.

Having thus described my invention, I claim:

1. A buffing wheel comprising an endless band buffering element of fabric material, folds in said element forming an annular disk, a flat disk-shaped hub for mounting said element, fingers spaced around the periphery of the hub and having outwardly tapering edges, said buffering element having elongated openings therein generally shaped to conform to the fingers and each being narrower than the tapered receiving portions thereof whereby the fabric around the opening is stretched in said narrower direction and the size of the opening in the other direction is reduced thereby effecting pressure against and around the finger, a retainer lock for each finger, said lock having at one end an enlarged retainer portion with an offset and an opening therein and at its other end a locking button and a hook, said hub having openings therein between each finger and the axis of rotation for receiving said button and hook, the end of the finger projecting through the opening in the offset portion of the retainer, said buffering element being applied and locked to the hub for embracing a finger and a retainer lock and locked thereon on one side by the tapered edges of the finger and on the other side by the enlarged retainer portion, said pressure exerted by the stretched fabric around the mounting opening maintaining the interengagement of said finger and lock.

2. The method of making a buffering wheel fabric which comprises, cutting a strip of fabric of proper length and width, stitching the ends of said strip to form an endless tubular band, folding portions of said strip across the width thereof to provide rectangularly shaped pleats of multiple thickness uniformly sized and spaced along the length of the band and having a portion of single thickness of the band connecting each pair of adjacent pleats, stitching said strip and pleats medially of the length thereof, further folding said strip across the width thereof between adjacent pleats to form additional rectangularly shaped pleats, folding said folded pleated strip along and outwardly of said medial stitching to form an annular disk adapted for mounting around the periphery of a buffering wheel, and in the sides of said disk forming pleats having overlapping folds extending generally radially of the buffering wheel.

3. A buffering wheel comprising an endless band buffering element of fabric material folded medially lengthwise to form an annular disk and having mounting openings therein, a disk-like mounting hub having peripherally spaced and outwardly tapered mounting fingers, the fabric being arranged when forced at an opening along a mounting finger to stretch and exert pressure thereagainst, and a retainer lock for each finger having one end enlarged for holding the mounted band thereon and its other end extending along the finger through the fabric opening and terminating in a hook to engage in an opening in the finger, the cooperation of parts being such that when said enlarged end of the lock is forced against the fabric and along the tapered finger to a hook engaged position the stretched fabric around the opening exerts tension on and maintains said finger and lock in hook engaged position.

4. A buffering wheel comprising an elongated strip of fabric material forming a tubular band,

folds widthwise of the band forming pleats spaced therealong, a seam extending medially lengthwise of the band securing the pleats thereto, said pleats having mounting openings therethrough and spaced along said seam, a mounting hub, outwardly tapered fingers peripherally spaced around the hub, the space between adjacent mounting openings of the band being greater than the space between adjacent fingers, of the hub, the fabric being arranged when forced at each opening along a mounting finger to stretch and exert pressure thereagainst, a retainer lock for each finger having one end enlarged for holding the mounted band on the hub and its other end extending along the finger through the fabric opening and terminating in a hook to engage in an opening in the finger, the cooperation of parts being such that when the enlarged end of the lock is forced against the fabric and along the tapered finger to hook engaged position the stretched fabric around the opening effects tension on and maintains the finger and lock in hook engaged position, and a pocket in said folded band at each finger formed when the band is medially folded upon itself into an annular disk and additional pleats are formed by the difference in spacing of the openings and fingers, portions of the sidewalls between said additional pleats forming the sides of the pocket and the ends of the pocket being formed of portions of said widthwise pleats extending between the disk sidewalls.

5. The method of making a buffering wheel fabric which comprises, cutting a strip of fabric of proper length and width, joining the ends of said strip to form a tubular band, folding portions of said strip across the width thereof to provide pleats of multiple thickness at spaced intervals around the periphery of the band having a portion of single thickness of the band connecting adjacent pleats, stitching said strip and pleats medially of the tubular band, and folding said band along said medial stitching to form an annular disk adapted for mounting around the periphery of a buffering wheel.

6. The method of making a buffering wheel fabric which comprises, cutting a strip of fabric of proper length and width, joining the ends of said strip to form a tubular band, folding portions widthwise of said strip upon itself to form pleats of multiple thickness of uniform rectangular shape and size spaced evenly around the periphery of the band and having a portion of single thickness of the band connecting each pair of adjacent pleats, stitching said strip and pleats medially of the tubular band, folding said band along and outwardly of said medial stitching to form an annular disk adapted for mounting around the periphery of a buffering wheel, and forming pleats in the sides of said disk around the circumference thereof.
